CLAIM

The ornamental design for a soap dispenser with drip tray, substantially as shown and described.

DESCRIPTION

FIG. 1 is a front, raised perspective view of a soap dispenser according to the invention;

FIG. 2 is a front view of the soap dispenser of FIG. 1;

FIG. 3 is a rear view of the soap dispenser of FIG. 1;

FIG. 4 is a right side view of the soap dispenser of FIG. 1;

FIG. 5 is a left side view of the soap dispenser of FIG. 1;

FIG. 6 is a top view of the soap dispenser of FIG. 1;

FIG. 7 is a bottom view of the soap dispenser of FIG. 1; and,

FIG. 8 is a front, lowered perspective view of the soap dispenser of FIG. 1.

The dashed dot lines immediately adjacent to the shaded areas in the figures represent the boundaries of the claimed design. The broken lines in the figures illustrate the portions of the soap dispenser with drip tray that form no part of the claimed design. None of the broken lines form any part of the claimed design. The soap dispenser with drip tray is shown with a symbolic break in its height. The appearance of any portion of the article between the break lines forms no part of the claimed design.
